US00D686345S

(12) **United States Design Patent**
Mugge et al.

(10) **Patent No.:** US D686,345 S
(45) **Date of Patent:** ** Jul. 16, 2013

(54) **MOLDED SURFACE OF A CONCRETE PRODUCT**

- (71) Applicant: **Anchor Wall Systems, Inc.**, Minnetonka, MN (US)
- (72) Inventors: **Jimmie L. Mugge**, Inver Grove Heights, MN (US); **Jay J. Johnson**, Star Prairie, WI (US)
- (73) Assignee: **Anchor Wall Systems, Inc.**, Minnetonka, MN (US)
- (**) Term: **14 Years**
- (21) Appl. No.: **29/436,872**
- (22) Filed: **Nov. 9, 2012**

Related U.S. Application Data

- (62) Division of application No. 29/395,652, filed on Mar. 5, 2012, now Pat. No. Des. 673,695, which is a division of application No. 29/374,249, filed on Jul. 18, 2011, now Pat. No. Des. 657,889, which is a division of application No. 29/372,782, filed on Jan. 10, 2011, now Pat. No. Des. 643,942, which is a division of application No. 29/370,143, filed on Jun. 9, 2010, now Pat. No. Des. 632,807, which is a division of application No. 29/315,040, filed on May 19, 2009, now Pat. No. Des. 620,134.

(57) **CLAIM**

The ornamental design for a molded surface of a concrete product, as shown and described.

DESCRIPTION

FIG. 1 is a front view of a molded surface of a concrete product, according to our new design;

FIG. 2 is a right side view thereof;

FIG. 3 is a left side view thereof;

FIG. 4 is a top view thereof;

FIG. 5 is a bottom view thereof; and,

FIG. 6 is a perspective view thereof.

The broken lines in all views are included for the purpose of illustrating portions of the concrete product that form no part of the claimed design.

1 Claim, 6 Drawing Sheets
